HANDLES FOR RAISING AND LOWERING
SEWING MACHINES.

Anthony J. Matuzas, Union, N. J., assignor to The Singer Manufacturing Company, Elizabeth, N. J., a corporation of New Jersey

Application July 1, 1954, Serial No. 440,611

3 Claims. (Cl. 112—258)

This invention relates to sewing machines and more particularly to a raising and lowering handle therefor and to means for maintaining said handle in any of several selected positions.

It is common practice, as exemplified by the disclosure of U. S. Patent No. 1,820,527, to mount a sewing machine in a so called "drop-head" table or cabinet in order that the sewing machine may be lowered to a concealed position or raised to an operative position. While many of the prior art structures for raising and lowering sewing machines have been found to be quite satisfactory, some difficulty has been experienced and, therefore, the primary object of the present invention is to provide an improved means for raising and lowering a sewing machine in a drop-head table or cabinet.

Another object of the invention is to provide a sewing machine with an improved easily accessible handle that may advantageously be used to raise and lower the sewing machine in a drop-head cabinet.

A further object of the invention is to provide an improved sewing machine lifting and lowering handle that may be maintained in any of several selected positions.

A still further object of the invention is to provide a sewing machine with a handle especially adapted to be used when raising and lowering a sewing machine in a drop-head cabinet.

Other objects and advantages of the invention will become apparent as the following description is read in connection with the accompanying drawings wherein:

Fig. 1 is a transverse vertical sectional view showing a sewing machine embodying the present invention lowered into a drop-head type table;

Fig. 2 is an enlarged view of a portion of the sewing machine as seen along the line 2—2 of Fig. 1;

Fig. 3 is a cross sectional view taken along the line 3—3 of Fig. 2 and showing the handle in an extended position; and

Fig. 4 is a view similar to Fig. 3 but showing the handle in the retracted position.

Referring now to the drawings, Fig. 1 illustrates a sewing machine cabinet or table 11 having front and back walls 12 and 13, and a horizontally disposed top wall 14 formed with a suitable sewing machine receiving opening 16. A flap 17, by means of a hinge 18, is adapted to be swung upwardly, as indicated by solid lines, or downwardly, as indicated by dotted lines. The free edge of the flap 17 carries an abutment 19, the purpose of which will hereinafter be described. A sewing machine 21 which may be of the same general type as that more fully disclosed in U. S. patent application Serial No. 386,684, filed Oct. 19, 1953, now Patent No. 2,756,703, granted July 31, 1956, and U. S. design patent application, Serial No. D.27,463, filed Nov. 6, 1953, now Design Patent No. 173,369, November 2, 1954, is supported from a rear portion of the top wall 14 by means of a pair of hinges, only one of which is shown. Each hinge has a leaf 22 secured to the top wall 14 by means of a screw 23 and

2

a movable element 24 pivoted to the leaf 22 and detachably connected to the sewing machine 21. The sewing machine comprises, among other elements, a bed 26 which is substantially horizontal when the sewing machine is in the raised operative position (dotted line position in Fig. 1), a bracket-arm standard 27 upstanding from said bed 26, and an arm 28 supported on the upper end of said standard 27 and terminating in a head 29 having a face-plate 31. The arm 28 is open at its upper portion so as to form a substantially trough-shaped unit and this opening is closed by a cover-plate 32 which joins the open top of the sewing machine arm along a plane that is substantially parallel to the bed 26 and is removably secured in position by screws only one of which is shown at 33. One end of the cover-plate 32 joins the top closed portion of the head 29 along a meeting line indicated by the numeral 34 (Fig. 2). The cover-plate 32, at a location adjacent to the meeting line 34 and to the rear edge 35, is provided with a portion 36 adapted to accommodate a raising and lowering T-shaped handle, indicated generally by the numeral 37. The handle 37 comprises a cylindrical support-shank 38, to the upper end of which is secured a horizontally extending hand-grip 39. In other words, the axis of the hand-grip 39 is parallel to the plane of the bed 26. The shank 38 has a longitudinally extending narrow slot 41, the end of the slot 41 adjacent to the hand-grip 39 terminating as at 42. The other end of the slot 41 is closed by a diametrically extending pin 43, which may be force fitted into a diametrically extending hole formed adjacent to the end of the shank 38 which is remote from the hand-grip 39. The portion 36 of the cover-plate 32, for accommodating the handle 37, includes a downwardly extending or depending lug 44 which is provided with a bore 46 extending from outside the cover 32 to below the lower surface thereof, and depending at an angle of forty-five degrees (45°) with respect to the plane on which the cover 32 joins the open top of the arm 28. In other words, the shank 38 is supported so to remain fixed in a plane 40 that intersects the bed 26 at an angle that is substantially forty-five degrees (45°). The bore 46 slidably accommodates the previously mentioned shank 38. The lug 44 is also provided with a second bore 47, the central axis of which passes at right angles through the central axis of the first bore 46. The end of the bore 47, which is located beyond the intersection between the two bores, houses a helical spring 48 and a slug 49. The spring 48 presses the slug 49 against the upper surface of the shank 38 and thereby provides a friction means which prevents the shank 38 from rattling in the bore 46 and at the same time assures that the shank 38 will remain in either an extended or a retracted position depending on the position to which it is moved. The end of the second bore 47 45 which is located below the intersection between the two bores is closed with a press fitted stop-pin 51, one end of which enters the narrow slot 41 in the shank 38; thereby insuring that the shank 38 cannot be twisted and also, because of pin 43, limiting the extent to which the shank 38 can be withdrawn from the bore 46. The portion 36 50 of the cover 32 also has a recess 52—52 for receiving the hand-grip 39 when the said hand-grip is in the retracted position shown in Fig. 4. As best seen in Fig. 2, the recess 52—52 has two portions, one on each side of the shank 38 and thus the two ends of the hand-grip 39 are received in the recess. In order that the operator may easily move the hand-grip 39 from the retracted position shown in Fig. 4 to the extended position shown in Fig. 3, the portion 36 of the cover 32 has been provided with a thumb receiving recess 53 which extends horizontally 55 beyond the hand-grip receiving recess 52. The portion 36 has also been provided with two finger-receiving re- 60

cesses 54 and 56 which extend vertically below the hand-grip receiving recess 52.

The handle 37 can be converted into a freely rotating handle by removing the pin 51, by eliminating the slot 41 and by replacing the pin 43 with a longer pin, i. e. with a pin that has a longitudinal dimension that is greater than the diameter of the shank 38. Removal of the pin 51 and the slot 41 allows the shank 38 and the hand-grip 39 to rotate freely, and substitution of a long pin for the short pin 43 provides a means for preventing the shank 38 from being removed from the bore 46 during normal operation of the device.

Operation

Under ordinary circumstances, if it is assumed that the sewing machine 21 is lowered into the drop-head cabinet 11, the hinged flap 17 will be in the lowered position shown in Fig. 1 by dotted lines, and the top-wall, including the sewing machine receiving opening 16 will be covered by a hinged cover member (not shown). To use the sewing machine 21 the operator first will raise the unshown hinged cover member and will move the hinged flap 17 to the position shown in solid lines in Fig. 1. Then, preferably using the right hand, the operator will reach into the cabinet 11 and if the handle 37 is in the retracted position shown in Fig. 4, the operator will place his right thumb in the recess 53, his index finger in the recess 54 and either his middle or ring finger in the recess 56. This will permit the operator to exert a pull on hand-grip 39, thereby moving the handle from the retracted position shown in Fig. 4 to the extended position shown in Fig. 3. Next, the operator will grasp the hand-grip 39 in the manner shown in Fig. 1 and raise the sewing machine 21 from the lowered position to a super elevated position, not shown, but slightly above the operative position shown by dotted lines in Fig. 1. This super elevated position of the sewing machine allows the operator to lower the flap 17 to the dotted line position shown in Fig. 1. When the flap 17 has been lowered, the sewing machine 21 is lowered until the free end of the bed 26 rests on the abutment 19 in the manner shown in dotted lines in Fig. 1. Then the operator moves the handle 37 from the extended position shown in Figs. 1 and 3 to the retracted position shown in Fig. 4. When the operator has completed the sewing and desires to move the sewing machine to the stored position, the handle 37 is extended and grasped by the operator who then by means of the handle 37 raises the sewing machine 21 to the super elevated position (previously mentioned but not shown) and then raises the flap 17 to the position shown by solid lines in Fig. 1. Thereafter, the sewing machine 21 is lowered into the cabinet and the flap 17 is lowered.

From the foregoing, it is evident that the present invention has provided a much improved means for assisting the operator in the task of raising and lowering the sewing machine in a drop-head type table or cabinet. It will also be appreciated that the here described drop-head cabinet and sewing machine are arranged so that, when the sewing machine is in the stored position shown in Fig. 1, the handle 37 is easily accessible from the front of the cabinet or table 11. Also, when the sewing machine is in the normal sewing position, the handle 37 is disposed at the back of the bracket-arm 28 and thus is out of the way of a person operating the sewing machine.

Having thus described the nature of the invention, what I claim herein is:

1. A sewing machine comprising in combination an up-

wardly open bracket-arm; a cover-plate for closing the opening in said bracket-arm, said cover-plate being provided with a first bore which extends at an angle of approximately forty-five degrees (45°) with respect to the plane of said cover-plate, and said cover-plate being provided with a second bore, said second bore intersecting said first bore; a handle having a shank and a hand-grip, said shank being slidably disposed in said first bore; means in said second bore preventing said shank from turning; and means retaining said shank in said first bore.

2. A sewing machine comprising in combination an upwardly open bracket-arm; a cover-plate for closing the opening in said bracket-arm, the upper surface of said cover-plate having a plurality of recesses; a depending lug formed as part of said cover-plate, said lug being provided with a first bore which extends at an angle of approximately forty-five degrees (45°) with respect to the plane of said cover-plate, and said lug being provided with a second bore which intersects said first bore at right angles thereto; a handle having a shank and a hand-grip formed at right angles to said shank, said shank being slidably disposed in said first bore and being provided with a longitudinally extending narrow slot, closed at both ends; a slidable slug and a biasing spring therefor located in one portion of said second bore; a press fitted stop pin disposed in another portion of said second bore and having one end entering the narrow slot in said shank; and a pin press-fitted into said shank and adapted to be engaged by said stop pin when said handle is in an extended position; said recesses in the upper surface of said cover-plate being adapted to receive said hand-grip and providing means for gripping said hand-grip.

3. A sewing machine comprising in combination a bracket having an upright standard and an overhanging hollow arm supported from said standard, a head carried by the free end of said arm; sewing instrumentalities carried by said head; a driving shaft for driving said sewing instrumentalities, said shaft extending from said standard through the hollow of said arm to said head, and thereby occupying a portion of the hollow of said arm, the outer surface of said arm being provided with a recess; a lug carried by said hollow arm and extending from an inner surface thereof, said lug being provided with a bore extending upwardly and at an angle and completely through said arm; a handle having a shank and a hand-grip, the hand-grip being formed at an angle with respect to said shank, and said shank being slideable in said bore, from a raised position in which the hand-grip and a portion of said shank are above the outer surface of said arm, to a lowered position in which a portion of said hand-grip is located in the recess in said arm and the lower portion of said shank extends below the upper portion of the inner surface of said arm and enters that portion of the hollow of the arm not occupied by said shaft; and means engaging said shank to limit the outward movement thereof, the recess in said arm providing means to limit the inner movement of said shank.
